UNITED STATES PATENT OFFICE

JOHN C. HOPKINS, OF LAKEWOOD, OHIO, AND ALFRED OSOLIN, OF CLEVELAND, OHIO

MUD GUN

Application filed July 1, 1929. Serial No. 375,252.

This invention relates to mud gun mechanisms, and more particularly to mud guns for closing blast-furnace tap-holes, and has for one of its objects the provision of an improved gun of the screw type employing a single screw to force the mud into the hole.

Another object is to provide a novel arrangement for feeding the mud from the supply hopper into the gun barrel.

10 A further object is to provide a novel nozzle design on the gun barrel which, due to its taper, will rapidly recede from the clay when the gun is being pulled out of the tap-hole, thereby causing a substantial saving of clay
15 material and labor in maintaining the clay wall work.

A still further object is to provide a gun mechanism having means for automatically locking the gun carriage to the furnace when the gun is moved into operative position.

Figure 1 is a plan view showing a mud gun constructed in accordance with this invention in operative position on a furnace.

25 Figure 2 is a side elevation thereof.
Figure 3 is a plan view, partly in section,

Figure 4 is a sectional elevation taken on the line IV—IV of Figure 3.

30 Figure 5 is a transverse sectional view taken on the line V—V of Figure 3.

Figure 6 is a rear end view of the gun showing the drive mechanism.

Referring more particularly to the drawings, the letter A designates a portion of a blast-furnace wall. The wall A is of usual

and well known construction and has the usual iron tap-hole 3 which opens into an iron runner-trough 4.

40 The mud gun is designated generally by the letter C and is mounted on a horizontally swinging carriage B. The carriage B may

be of any preferred construction or design but is generally of a platform type and is mounted for rotary movement about a pedestal support 5. The support 5 has a worm

tar support 3. The support 3 has a worm-wheel 6 fixedly mounted thereon and a worm 7 is journaled on the carriage B and meshed with the worm-wheel 6.

50 The worm 7 is adapted to be driven by a

motor 8. A second motor 9 is provided for operating a gun seating and unseating mechanism consisting of a shaft 9^a having a link and lever connection 9^b with the gun and carrying a rack 9^c which is meshed with a drive-pinion 9^d of a gear reducing unit 9^e which is coupled with the armature shaft of the motor 9.

The mud gun C is supported on links 10 suspended from the carriage B and is movable relative to the carriage for movement into and out of the tap-hole 3. 60

The gun C comprises a gun barrel 12 in the form of a screw conveyer housing having a nozzle 13 removably bolted to its forward end, as at 14. The nozzle 13 has a taper toward its forward end of more than ten degrees so that it will readily come out of the iron hole 3 without damaging the clay setting 15 at the iron hole 3 and in the trough 4. Due to the taper of the nozzle, the nozzle will recede much faster from the clay when the gun is being pulled out of the hole 3 and, therefore, substantial saving of clay and labor of maintaining the clay wall work is effected.

A bearing housing 17 is secured to the rear end of the barrel 12 and a gear housing 18 is secured to and closes the rear end of the bearing housing 17. The conveyer housing or barrel 12 has its upper wall stepped upwardly intermediate its ends to form a hopper 19 in which the clay or mud to be used in stopping the hole 3 is stored. 80

A screw conveyer 20 is mounted in the barrel or conveyer housing 12 and extends from the rear end of said housing forwardly into the nose of nozzle portion 13. The conveyer 20 is provided with spiral flights 21 and is adapted to be rotated in a counter-clockwise direction. 85 90

A feed-roller 22 is mounted on one side of the conveyer housing 12 with its axis parallel to the longitudinal axis of the conveyer and projecting through the side wall of the hopper 19. The roller 22 is adapted to be rotated in a clockwise direction.

The conveyer 20 is adapted to force clay or other plastic materials from the hopper 19 through the conveyer housing or gun barrel 101

12 and out of the nozzle 13 under pressure to plug the tap-hole 3 of the furnace. Therefore it is essential that there be no back-flow of the clay or plastic material.

- 5 In order to prevent a back-flow of the clay or plastic material, the forward end wall of the hopper at its point of juncture with the conveyer housing, as at 23°, is parallel with the angle of the flight on the conveyer 20.
- 10 By forming the lower end of the forward wall of the hopper on the angle, as above described, the flight on the conveyer will simultaneously close the space between the forward edge of the hopper and the conveyer flight as 15 said conveyer is rotated. As the feed roller 22 is rotated in the opposite direction to that of the conveyer 20, the clay is fed between the conveyer flights and prevented from sticking to the side of the hopper 19.
- 20 The conveyer 20 is fixedly mounted on a shaft 23, and the rear end of this shaft which is journaled in bearings 24 and 25 in the bearing housing 17, is extended beyond the bearing housing into the gear housing 18, and 25 carries a gear 26 which is meshed with the feed-roller driving gear 27 and the drive-pinion 28 of a drive-motor 29 carried by the gun. The motor 29 may be powered by electricity, fluid or other means, as desired.
- 30 The feed-roller 22 is provided with a shaft 30, and one end of said shaft is journaled in a bearing 31 in the gear housing 18 and carries the gear 27, while the other end of said shaft is journaled in a bearing 32.
- 35 The motor 29 is adapted to rotate the shaft 23 counter-clockwise and consequently, since the shaft 23 and conveyer 20 are secured together, the conveyer 20 will likewise be rotated in a counter-clockwise direction, while 40 the shaft 30 and feed-roller 22 will be rotated clockwise since the shaft 30 is connected directly to the feed-roller 22 and is driven by the gear 27 through the gear 26.

The shaft 23 is provided with a thrust bearing 33 mounted between a shoulder 33a on the shaft and the gear housing 18. The bearing 33 is adapted to take up the rear thrust of the conveyer as it forces the clay through the gun.

50 The carriage B is adapted to be automatically locked to the furnace wall when the carriage is swung around into operative position.

A coupler clevis 35 is mounted on the furnace wall A, and a second clevis 36 is mounted on the front of the carriage and carries a vertically disposed bar 37. A latch 38 is pivotally mounted in the clevis 35 for horizontal movement. A coupler locking-pin 39 is mounted for vertical movement through a 60 guide bracket 40 and suitable apertures 41 in the clevis 35. The pin 39 is adapted to be raised above the upper face of the latch 38 and the latch is adapted to be swung back under the pin when the coupling is in inoperative position. When the carriage is moved

into operative position the bar 37 will strike or engage the latch 38 and swing it around its pivotal mounting so as to hold the bar 37 between the latch 38 and clevis 35. When the latch 38 is moved about its pivot by the 70 bar 37 the pin 39 will drop through the apertures 41 in the clevis and lock the latch 38 against retraction until said pin 39 is raised above the latch.

A length of cable or the like 43 is secured 75 to the upper end of the pin and is trained over suitable sheave wheels or other guides (not shown) to a point handy to the operator.

Throughout this specification the word "mud" is to be construed broadly and is meant 80 to cover clay or any other plastic material.

In operation, the hopper 19 will be filled with mud, and the carriage B will be operated to swing the gun around into operative position. 85

When the carriage B has moved around into operative position the coupling mechanism will lock the carriage in position. The motor 29 will then be started to operate the conveyer 20 and feed-roller 22 simultaneously 90 in opposite directions so as to cause the mud, clay or other material to be pulled out of the hopper 19 and forced through the gun barrel or conveyer housing 12 and out of the nozzle 13 in a continuous stream until the 95 hole 3 is filled or plugged.

While we have shown and described certain specific embodiments of our invention it will be understood that we do not wish to be limited thereto, since various modifications 100 may be made without departing from the scope thereof, as defined in the appended claims.

We claim:

1. A mud gun for closing furnace tap-holes 105 comprising a mud hopper, a screw conveyer housing below and communicating with said hopper, a single screw conveyer mounted in said housing and extending under said hopper, the forward end wall of said hopper at 110 the point of junction with said conveyer housing being inclined on an angle parallel with the angle of the flights on said conveyer so that the flights on said conveyer will simultaneously seal the entire length of the forward edge of the hopper and prevent back-flow of the mud being forced forward by said conveyer, a feed-roller journaled on said conveyer housing and extending through an opening in the side wall of said mud hopper, 115 and means for simultaneously driving said conveyer and said feed-roller.

2. The combination with a blast-furnace, of a clay gun mechanism comprising a swinging carrier, a clay gun mounted on said carrier, a coupling member on said carriage, a cooperating coupling member on said furnace, a bar on said coupling member on said carriage, a swinging latch on said coupling member on said furnace, said latch being 120 125 130

adapted to automatically engage around said bar when said coupling members are moved together, and means for automatically locking said latch against reverse movement when it is moved to engage around said bar.

3. The combination with a blast-furnace, of a clay gun mechanism comprising a swinging carrier, a clay gun mounted on said carrier, a coupling member on said carriage, a 10 cooperating coupling member on said furnace, said coupling members being adapted to be automatically locked together when said carriage is moved toward said furnace to thereby lock said carriage against reverse 15 position.

In testimony whereof, we have hereunto set our hands.

JOHN C. HOPKINS.
ALFRED OSOLIN.
